Samuel D. Vose, of Albany, N.Y.
Letters Patent No 498 Dated Sep. 14th 1852 Ante-Dated Mar. 14, 1852

The schedule referred to in these Letters Patent and making part of the same

To all whom it may concern:

Be it known that I, Samuel D. Vose, of Albany, County of Albany, State of New York, have invented or produced a new ornamental design for a bookcase stove, and I do hereby declare that the following is a full, and exact description of the same reference being had to the annexed drawings affixed to and making part of this specification.

Fig 1 Represents the stove perspective.

Fig 2 " front with the configuration partially detailed with more exactness a section of one half of the front being fully drawn.

Fig 3 Represents the side.

T " " top

B " " bottom

S " " sides

My invention consists in the combination of the several mouldings & ornaments as arranged in the whole stove and is not easily described in words and reference is therefore made to the drawings.

I do not claim any detailed part of the mouldings or configuration.

What I claim as my invention and desire to secure by)
